IRONING BOARD PAD

Application filed July 21, 1932. Serial No. 623,845.

This invention relates to improvements in ironing boards, ironing rests and the like but more particularly to a pad to be used in connection therewith, and its objects are as follows:—

First, to make the cover of woven fabric and to use a vulcanizable coating for affixing it to its base, said coating having that property which enables pulling the cover away in tact or peeling it from said base without damage either to the base or cover in the event of its being soiled, thus leaving the surface of the base clean for the vulcanization of a fresh cover.

Second, to provide an ironing pad of a base structure suitable to enable the affixation of a cover thereto by vulcanization, the normal operation of ironing serving to maintain the security of the cover.

Third, to provide an ironing pad of sponge rubber which has the property of absorbing the excessive heat and steam, which excessives escape at openings around the outer edge, said pad including covers on opposite sides of and coextensive with the sponge rubber part, these covers having the additional property of supporting the sponge rubber against undue distortion and collapse under pressure of the iron during the operation of ironing.

Fourth, to provide an ironing pad of resilient or elastic material, said material reacting upwardly against the downward ironing pressure, thereby enabling more perfect ironing by virtue of an actual pressure on the nether side of the goods as well as on the top side.

Other objects and advantages will appear in the following specification, reference being had to the accompanying drawing in which

Figure 1 is a perspective view of the improved ironing board pad.

Figure 2 is a detail perspective view illustrating a corner of the fabric cover peeled from the sponge rubber base to disclose the perforations in the latter.

Figure 3 is a sectional view illustrating the action of the pad on a piece of goods under heat and pressure.

Figure 4 is a detail sectional view illustrating the action of a sponge rubber pad from which the perforations of Figure 3 are omitted.

Figure 5 is a detail sectional view of a sponge rubber pad in which the pores of the cover have been made to diminish toward the opposite sides so as to leave those sides substantially smooth, this type of the pad being without the fabric cover in the preceding forms.

Figure 6 is a detail view of a portion of striped goods illustrating the distortion of both the stripes and warped threads when the goods is ironed on a common type of ironing board.

It is common knowledge that ironing boards such as used in households are not entirely satisfactory from several standpoints. Such boards are generally padded with felt, cotton batting or the like and then covered with a fabric sheet which is designed for the purpose. This sheet is ordinarily stretched tight, but under the action of ironing, taking the motions of the iron, the heat and steam together, the cover soon shows a tendency to become loose and works up a wave which buckles and rolls ahead of the iron.

This buckling and rolling of the cover frequently causes creases in the goods being ironed by virtue of the fact that the roll has a tendency to make the goods buckle also and produce an obstruction which the iron will surmount. The iron thus produces an undesirable and unsightly crease in the goods, and it becomes necessary to smooth the goods out again and do that portion of the surface over.

Another bad effect of the loose cover is its tendency to stretch and distort the goods. Figure 6 is an illustration of an actual piece of starched goods which was ironed on a conventional board. This goods has parallel stripes 1. The looseness of the cover actually caused the distortion of the stripes as illustrated and also caused a distortion of the warp threads 2.

Another undesirable feature of known ironing boards is the lack of resiliency. In ironing goods having seams and buttons it is not uncommon for the operator to use one or

two towels as an additional base, providing a place for the buttons and seams to sink into so that there may be a level top surface over which to iron.

5 The invention overcomes the foregoing difficulties and has several additional outstanding advantages over known modes of padding and covering ironing boards. The pad, generally designated 3 comprises a 10 sponge rubber base 4. Sponge rubber has a myriad of pores which make it absorbent. When the base of an ironing pad is made of sponge rubber it absorbs excessive heat and steam, permits the excessives to escape and 15 yet maintains a desirable degree of warmth for the ironing operation.

The base 4 in one form of the invention (Figs. 2 and 3) is provided with cross perforations 5 which are particularly effective in 20 permitting the penetration of heat and steam in the direction of the arrows 6, (Fig. 3) and the escape thereof in the direction of the arrows 7. These perforations are large in comparison with the normal pores 8 of the 25 sponge rubber base, and while said pores absorb some of the heat and steam as outlined above, yet most of these elements are taken care of by the perforations.

Covers 9 are affixed to the opposite sides of 30 the base 4. They are co-extensive with the sponge rubber base 4. These covers consist of what is known as rubberized material. Each cover has a coating 10 of rubber composition on one side, and this coating is herein 35 known as vulcanizable inasmuch as by means of it the respective cover 9 can be attached to a side of the base 4 by the application of heat and pressure. The covers serve to support the sponge rubber base 4 against distortion 40 and collapse under the action of the iron in the operation of ironing. Since the base is soft there might be the tendency of too much distortion under the pressure of the iron. The covers, being affixed as they are, hold 45 back on the soft base and tend to keep it in a firm condition.

When affixed as outlined above, the cover 50 9 is insured against slippage. It is not subject to any appreciable expansion or shinkage, either effect being compensated for by a slight yielding of the adjacent parts of the base. The cover will not buckle or roll ahead of the iron, and yet the vulcanizable coating 55 10 has this property that the cover may readily be peeled off should it be desired to replace it by a fresh cover.

For the last purpose the cover 9 is composed of a woven fabric. The warp and weft threads of the fabric impart to it that 60 strength which will enable the fabric peeling off without any possibility of the cover tearing as would be the inevitable result if the cover were composed of a short-fibred substance such as felt. In actual practice the 65 cover 9 may consist of canton flannel with

the rubber composition coating 10 on the side opposite to the nap surface.

It is of no little importance to note that the normal operation of ironing serves to maintain the security of the cover 9. That operation involves both pressure and heat, and each of these factors is ordinarily required in affixing the cover to the base. In Figure 3 each side of the base 4 is provided with a cover 9, thus making the pad reversible.

Figure 4 illustrates a similar duplication of the covers 9^a, that is to say, there is a cover on each side of the base 4^a. These covers are fastened on by rubberized coatings 10^a as before. It is the covers which have the rubberized coatings, and the covers are composed of woven fabric so that they can be peeled off for renewal.

But in Figure 4 the cross perforations 5 are omitted. The sponge rubber is virtually full of pores 8^a, and these are so connected that the steam and heat may have egress at the sides of the base 4 as illustrated by the arrows 11. This type of pad may not be as efficient as the type in Figure 3 because of the lack of corresponding cross perforations, but for some commercial purposes the type of pad in Figure 4 will be well suited.

The same principle prevails in Figure 5. 55 This is a type of pad in which fabric covers are omitted entirely. The largest pores 8^b in the sponge rubber base 4^b are in the center of the mass. From there they become graduated in size toward the respective sides of the base virtually disappearing as they reach strata of smooth rubber 12. These strata are smooth like the surface of a hot water bottle. The smoothness takes the place of the foregoing fabric covers. The smooth 60 faces can be washed and so kept clean. They have a limited porosity and consequently there will be a limited circulation of heat and steam through the base. There will be 65 some circulation although not to the extent in the form in Figures 3 and 4.

It will be understood from what has been stated, that the main purpose is to provide a pad for ironing boards, machines and the like composed of a sheet of sponge rubber which provides a firm yet yieldable base. When garments having outstanding seams, buttons or the like are to be ironed, such outstanding parts, (see the button B in Fig. 3) will be pressed into the base and below the surface so that the goods maintains an approximately level surface over which the hot iron can pass smoothly. This is a principle common to all of the forms of the invention.

Rubberized fabric can be bought on the 125 open market, and it is this type of fabric which is used for the covers 9, 9^a. The covers are affixed to the base 4, 4^a by vulcanization, that is to say by heat and pressure which respectively melts the rubberized coating and 130

causes it to combine with the side surfaces of the base.

The desirable peculiarity of the vulcanizable coating is that peeling off of the cover becomes possible. To this end the cover comprises a woven fabric which will not tear in the peeling off process. Being vulcanized in place the cover will stay in position during the operation of ironing and will not work up into folds or waves ahead of the iron thus causing a distortion of the fabric (Fig. 6) as occurs when ironing goods on an ordinary ironing board.

I claim:—

15 1. An ironing pad comprising a base of sponge rubber, and a cover for said base, said cover comprising a woven fabric having a vulcanizable coating, said coating uniting the cover with the base and being separable as a unit from the base to enable a replacement cover to be vulcanized to the base.

20 2. An ironing pad comprising a base of sponge rubber, and a cover for said base, said cover comprising a woven fabric having a vulcanizable coating, said coating uniting the cover with the base and being separable as a unit from the base to enable a replacement cover to be vulcanized to the base, said cover being coextensive with the base leaving the ends of the base unobstructed with the pores of the base exposed at said ends.

25 3. An ironing pad comprising a base of sponge rubber, a cover for a face of said base, said cover comprising a woven fabric having a vulcanizable coating, said coating uniting the cover with the base and being separable as a unit from the base to enable a replacement cover to be vulcanized to the base, and a second cover secured to the opposite face of the base.
